UNITED STATES PATENT OFFICE.

LAWRENCE C. STEELE, OF PITTSBURGH, PENNSYLVANIA.

METHOD OF MANUFACTURING SHEET METAL.

REISSUED

Application filed April 18, 1922. Serial No. 554,573.

To all whom it may concern:

Be it known that I, LAWRENCE C. STEELE, a citizen of the United States, and resident of Pittsburgh, in the county of Allegheny and State of Pennsylvania, have invented a new and useful Improvement in Methods of Manufacturing Sheet Metal; and I do hereby declare the following to be a full, clear, and exact description thereof.

10 My invention relates to a method of manufacturing sheet-metal.

In the present method of rolling sheets for tin-plate the heated bars are taken from the furnace in pairs and are passed one at a 15 time in succession through the rolls, the bars being fed by hand through the rolls and passed back over the top of the rolls for three or four passes. The rolled bars are then "matched" by placing one on top of the 20 other, and are put back in the furnace to be reheated, whereupon they are again brought out and passed together through the rolls. This heating of the matched-bars and passing them through the rolls is commonly 25 known as the "run-over pass". The purpose of this last-named rolling operation is more to reduce the thickness of the pack than to obtain elongation, so that the metal can be doubled by hand, which is done after this 30 rolling operation. After the doubling, the pack, which is 4-ply, is put back into the furnace, reheated, brought out, and repassed the required number of times through the rolls, when it is opened (this is done by pulling 35 the sheets apart with tongs), is doubled again to form 8-ply, re-heated, and passed through the rolls a sufficient number of passes to bring the pieces to the specified length. The sheets are then sheared into the 40 required sizes and the packs opened by hand, this being required because the sheets have stuck more or less together in the process of rolling. The sheets are then annealed and treated by subsequent operations to obtain 45 the desired product, such as tin-plate, sheet-iron, etc.

In this old method of handling the sheets in rolling, the bars, in the first instance when drawn from the furnace, were thrown on the 50 floor, where they were picked up by the roller by tongs to pass through the rolls. After the bars had been rolled they were matched on the mill-floor, and in this matching were liable to pick up grease, scale or dirt from said mill-floor, and as the subsequent dou-

bling was likewise done on the mill-floor, the sheets had further opportunity to pick up grease, scale or dirt, and in the rolling of the sheets this foreign matter would be rolled into the metal, and when the packs 60 were separated the defects caused by such dirt or scale would show up and the sheets would have to be thrown aside as wasters.

The object of my invention is to provide a method of manufacturing sheet-metal which dispenses with the "run-over pass" thereby doing away with the time and expense of the extra heating and rolling of the metal, and thereby greatly reducing the cost. 65 A further object of my invention is to eliminate the danger of scale, grease or dirt getting between the sheets when the sheets are matched or doubled on the mill-floor, thereby greatly reducing the waste and increasing the production accordingly for the same 70 amount of time and labor expended.

In the accompanying drawing I have illustrated suitable apparatus for carrying out my improved method, although it is understood that this apparatus may be modified or changed without effecting the scope 75 of my invention. Fig. 1 of the drawing is a plan view; and Fig. 2 is a side elevation.

In carrying out my improved method I 80 employ suitable heating-furnaces, such as indicated by the numerals 2 and 3, said furnaces being provided with the doors 4 and 5, respectively. The bars are heated in the furnace 2 and when withdrawn therefrom are placed on a suitable feed-table 6 which 85 feeds the bars up to the rolls 7. The bars are fed automatically to the rolls, and passing through said rolls are delivered on to the catcher 8, illustrated diagrammatically. 90 This catcher consists, generally of the skids 9 to receive the sheet or pack; the rotary carrier 10 which lifts the material from the skids and lifts it up to the conveyer 11 which in conjunction with an endless chain on the carrier 10 and the endless chain 12 delivers 95 the material over the top roll to the feed-table 12^a to be returned through the rolls. 100 In this manner the metal is rolled back and forth through the rolls without coming in contact with the mill-floor until it has been reduced to the proper gauge, whereupon the sheets, after the final pass, are delivered to the feed-rolls 13 to be discharged on the feed-table 14 composed of the conveyers 15 105 which travel at right angles to the travel of 110

the rolls 13. From the table 14 the sheets are delivered to the inclined feeder 16 which delivers them to the raised platform 17, where the sheets are matched and doubled. 5 This doubling is preferably done by a doubling machine, such as that illustrated and described in a patent granted to me March 15, 1910, No. 952,052, although it is apparent that the doubling may be done by hand. The 10 platform 17, being raised above the mill-floor, is free from the grease, dirt and scale of said mill-floor, and consequently there is no liability of the sheets getting any of such grease, scale or dirt between them which results in defective sheets. 15

By my method, up to this point, I am able to dispense with the "run-over pass," as the metal has been reduced in the rolls, without reheating, to a gauge suitable for 20 doubling, so that when the plates are delivered to the platform 17 the matching and doubling takes place as one operation.

The sheets thus matched and doubled into 4-ply are then delivered to the feed-table 25 18 to be delivered into the furnace 3, a supplemental feed-table 19 being employed to lower the plate down through the opening 5 of the furnace. In this way, by having the doubling platform 17 and the feed-table 18 30 at a proper height, there is no interference with the operators working around on the mill-floor below. The doubled-pack, after being properly heated in the furnace 3, is withdrawn and delivered to the feed-table 35 6, which is shifted over in position to receive the pack as it comes from the furnace 3, as clearly indicated in dotted lines, Fig. 1, and the pack is delivered to the rolls to be passed back and forth through the same 40 until reduced to the proper gauge, whereupon the pack is delivered by the feed-rolls 13 to the tables 15 and 16 to be discharged on the doubling platform 17 where the pack is again doubled into 8-ply. The 45 pack is again delivered to the furnace 3 to be reheated and delivered back to the rolls for further rolling, and when the metal has been brought to the proper length it is thrown out in the rear for cooling. While 50 I prefer to do the doubling at an elevation it may be done on the floor level in the rear of the mill, and carried thence by a con-

veyer to the furnace without coming in contact with the mill-floor.

By my method the bars, or the pack rolled therefrom, never come in contact with the mill-floor, and consequently do not pick up the scale, dirt or grease which results in so many wasters, the doubling and matching all being done at an elevation well above 60 the mill-floor. This does away with the congestion around the rolls where the matching and doubling are done on the mill-floor, and leaves more space for the operators, which makes it possible to reduce the 65 number of men required to do the work.

What I claim is:

1. The method of manufacturing sheet-metal consisting in rolling the heated bars back and forth in the rolls keeping the 70 metal from contact with the mill-floor during rolling until reduced to a gauge for matching and doubling, elevating the sheets to a point above the mill-floor, matching and doubling the sheets at this elevation, 75 and passing the sheets while still in the elevated position back to the heating furnace.

2. The method of manufacturing sheet-metal consisting in heating the bars in a furnace, delivering the heated bars from 80 the furnace to the rolls in a plane above the mill-floor, passing the metal back and forth through the rolls keeping the metal from contact with the mill-floor until reduced to a gauge for matching and doubling, elevating the sheets to a point above the mill-floor, matching and doubling at this elevation, and passing the sheets while in elevated position back to the heating furnace. 85

3. The method of manufacturing sheet-metal consisting in delivering the heated bars from the furnace to the rolls in a plane above the mill-floor, passing the metal back and forth through the rolls, keeping the metal from contact with the mill-floor, until 90 reduced to a gauge for matching and doubling, doubling the metal in the rear of the rolls, and conveying the metal in a plane above the mill-floor back to the heating furnace. 95

In testimony whereof I, the said LAWRENCE C. STEELE, have hereunto set my hand.

LAWRENCE C. STEELE.
